UNITED STATES PATENT OFFICE.

EDGAR H. MUMFORD, OF PHILADELPHIA, PENNSYLVANIA.

MOLD-TABLE.

1,066,835.

Specification of Letters Patent.

Patented July 8, 1913.

Application filed August 18, 1908. Serial No. 449,018.

To all whom it may concern:

Be it known that I, EDGAR H. MUMFORD, a citizen of the United States, residing at Philadelphia, in the State of Pennsylvania, have invented certain new and useful Improvements in Mold-Tables, of which the following is a specification.

This invention has reference to the provision of an improved form of apparatus for supporting molds in a foundry, and carrying them from one point to another at which they are poured, and then transferring them to still another point at which they are taken off the support and the castings taken out.

The first of the objects of this present invention is the provision of a device of the character specified, which will very much economize in the space necessary for handling molds in a foundry, and which will also handle said molds in a more satisfactory and economical manner. A further object of the invention is the provision of mechanism of this general type in which the molds after being poured are gradually elevated at a point at which they are above the sand floor, which latter is located above the mold floor or foundry floor, and thus a convenient means is provided for separating the sand and castings after they have cooled, and at an elevation from which the sand can be reconveyed through proper chutes and hoppers, to the molding machinery employed, and the castings also transferred to the machining department, by the action of gravity.

With respect to the saving in space above mentioned a further object of this invention is to eliminate the loss of space incident to the room required for movement of the transfer devices when traveling in a horizontal plane.

2.—To eliminate the loss of space incident to the employment of a return loop which is necessarily included in a horizontally moving mechanism and which necessarily occupies a large amount of room.

3.—To eliminate in a large measure such multiplicity of parts in one connected or continuous mechanism as produce liability to frequent failures.

4.—To secure greater certainty and reliability in operation and the avoidance of complete stoppages incident to the failure in one place of a mechanism which is continuous throughout the shop.

5.—To avoid the necessity of operating a transfer mechanism adapted to the requirements of an entire foundry output when as in slack times only a small portion thereof may be required.

The above as well as such other objects as may hereinafter appear, I attain by means of a construction which I have illustrated in preferred form in the accompanying drawing, wherein—

Figure 1 is a side elevation, somewhat diagrammatic, indicating an apparatus embodying my improvement, and Figure 2 is a front vertical view of the same.

In carrying out my invention I arrange an endless conveyer or carrier composed of the cables or chains 3 carrying shelves 4, the said endless carrier being adapted to travel around wheels 5 at the base, and other wheels 6 at the top of the supporting frame 7 which is of sufficient height to accommodate a number of mold shelves. The power for driving the carrier may be obtained as indicated, by means of gearing 8 driven by a motor or other suitable driving device 9 which in this instance is mounted near the head of the frame 7, upon the bracket supports 10 so as to be entirely removed and out of the way of the operators upon the foundry floor below. Located substantially on the same level as that of the brackets 10 I may arrange a sand floor 11 from which there are provided suitable hoppers 12 and down spouts or conductors 13 through which the sand may be returned to the proper place in proximity to the molding mechanism 14, which may be of any preferred type.

In the foundry floor 15 I preferably provide a depression indicated at 16, for clearance for the mold shelves, the direction of motion being that indicated by the arrow shown at 17.

At a point some distance above the floor 15 I arrange suitable shafts 18 carrying a couple of wheels 19 by means of which the conveyer or carrier with the shelves attached is pressed inward as shown on Figure 1, so as to afford free access to the upper surface of the molds one of which is indicated at 20, which are traveling upward on the mold shelves. The wheels 19 are preferably supported on short shafts 18 to insure clearance between said wheels so as to make room for any ladle supporting chain or other device incidental to the pouring

operation. The pouring is to be done by a suitable ladle indicated at 21, and the pressing inward of the carrier exposes the upper surface of the mold as stated, so that 5 the pouring operation may be more readily accomplished.

The operation of my invention is as follows.

The molds are first formed on suitable 10 molding machinery indicated generally at 14, and, after being completed and the cores set, are placed upon the depending shelves indicated on the left side in Figure 1, upon which they ride downward, around and upward 15 into the position indicated at 20 where the pouring may be accomplished, a portion of the carrier being arranged so as to permit such pouring. After the mold is poured, it continues to travel upward slowly step 20 by step, or continuously as circumstances require, and the casting gradually hardens and cools, until the mold when it reaches the top of the support is in condition for being taken out to effect a separation of 25 the sand and casting.

In order to avoid slipping, the conveyer is made of sprocket chain which engages with sprocket wheels at the top and bottom, or it may be constructed of cables with 30 suitable projections or buttons thereon engaging corresponding notches or depressions in the wheels 5 and 6.

Having thus described my invention and 35 illustrated its use, what I claim as new and desire to secure by Letters Patent, is the following:

1. In molding apparatus, an endless substantially upright carrier provided with a series of mold supports, a mold floor, a 40 sand floor thereabove at the downwardly moving side of the carrier, means whereby the sand may be transferred from the sand

floor to the mold floor and pouring means at the upwardly moving side of the carrier.

2. In molding apparatus, an endless substantially vertical conveyer provided with a series of mold supports, a molding machine adjacent the lower end of the conveyer at the downwardly moving side thereof, sand receiving means above the molding machine, means whereby the sand may be transferred from the receiving means to the molding machine, and pouring means adjacent the line of movement of the conveyer.

3. In molding apparatus, a plurality of operating floors one above another, a mold conveyer for elevating the molds from one floor to another, means for forming the molds on a lower floor, means for pouring the molds on a lower floor, and means for transferring the sand from the molds shaken out on the upper floor to the floor on which the molds are formed and adjacent to the forming means.

4. In molding apparatus, a plurality of operating floors one above another, an endless conveyer for elevating the molds from one floor to another, means on one side of the conveyer on a lower floor for forming the molds, means on a lower floor on the opposite side of the conveyer for pouring the molds, and means for transferring the sand shaken out of the molds on an upper floor to the floor on which the molds are formed, and adjacent to the forming means.

In testimony whereof I have hereunto signed my name in the presence of the two subscribed witnesses.

EDGAR H. MUMFORD.
